UNITED STATES PATENT OFFICE

MORTIMER L. PACKER, OF COLUMBUS, OHIO.

DEVICE FOR SUPPORTING ARTICLES IN AN ELECTROPLATING-BATH.

1,005,870.

Specification of Letters Patent. Patented Oct. 17, 1911.

Application filed February 3, 1911. Serial No. 606,320.

To all whom it may concern:

Be it known that I, MORTIMER L. PACKER, a citizen of the United States, residing at Columbus, in the county of Franklin and 5 State of Ohio, have invented certain new and useful Improvements in Devices for Supporting Articles in an Electroplating-Bath, of which the following is a specification.

10 The present invention relates to certain novel and useful improvements in a device for supporting articles in an electro-plating bath.

In carrying out my invention, it is my 15 purpose to provide a support of the class described, whereby the articles to be electroplated may be suspended in the bath, and whereby the electric current may be readily conducted to the main rod of the support 20 and to the individual supports from which the articles are suspended.

A further object of my invention is to provide a device of the type referred to 25 wherein the supports for the individual articles are so combined and correlated with the main body portion or rod of the device, that said individual supports may be readily connected to and removed from the main rod.

30 Still a further object of my invention is to provide a rod having an outer sleeve of insulated material, the individual supports for the articles to be electro-plated, passing through the main rod in such manner that 35 they may be readily inserted and removed therefrom, so that should one of the supports be broken or otherwise injured, it may be readily and quickly removed and a new one inserted.

40 It is also my aim to provide a support of the class described, embodying in its construction the desired features of simplicity and durability.

With the above recited objects and others of a similar nature in view, my invention consists in the construction, combination and arrangement of parts set forth in and falling within scope of the appended claim.

In the accompanying drawings—Figure 1 50 is a view in elevation of a device embodying my improvements, Fig. 2 is a cross sectional view taken on the line 2—2 of Fig. 1, Fig. 3 is a similar view taken on line 3—3 of Fig. 1, and Fig. 4 is a longitudinal sectional view 55 taken on the line 4—4 of Fig. 1.

Referring now to the accompanying draw-

ings in detail, the letter A designates a metallic rod, through which the current is adapted to be conducted to the bath, said rod having its upper end provided with a 60 hook portion as at 2, to engage with the ordinary cross bar 3, through which the current is conducted to the metallic rod A. Surrounding said rod is a sleeve 4 of insulating or non-conducting material, while passing at suitable intervals through the sleeve and rod, are transverse bores or openings 5, through which are adapted to be passed metallic rods or wires 6, bent into suitable form to support the article to be electro-plated. In the present instance, referring to Fig. 1, it will be seen that I have taken a short section of wire and after the same has been passed through the transverse bore 5, said wire is bent downward as at 7 and then 70 upward as at 8, so that the wire on each side of the rod is bent into an approximately V-shaped form, the center portion of the wire contacting with the conducting rod A, and receiving current therefrom. 75

While I have in the present instance, shown the suspending wire as bent into a peculiar form, I wish it to be understood that I do not limit myself to bending the wire in the manner shown in Fig. 1, for the 80 purpose of supporting articles, as said wire or rod may be bent into any form suitable for the articles to be supported.

From the above description, taken in connection with the accompanying drawings, 90 the construction and operation of my improved support will be readily apparent.

The articles are suspended from the individual supports or cross wires and the hook is then placed over the bar 3 and the current 95 turned on. Current flowing through the bar 3, passes to the rod A and thence through the individual supports, so that the article in the bath, may be rapidly and thoroughly electro-plated, in the well known manner. 100

It will be noted that I have provided an exceedingly simple form of support, and yet one which is especially adapted for the purpose of suspending the articles in an electro-plating bath. As heretofore stated, the individual suspending wires or rods, may be readily removed from the main rod A in case of breakage or other injury and it will only be necessary to withdraw the injured rod and insert a new one. Thus considerable time is saved, which is a decided advantage over those devices of this type wherein 105 110

the individual supports were soldered or otherwise secured to the main bar. Furthermore, by providing an insulated sleeve covering that portion of the rod in the bath, I
5 prevent such rod becoming electro-plated.

What I claim, is—

In an electro-plating rack comprising a vertical rod of conducting material, a support upon its upper end for conductive connection with a current wire, an insulating sleeve surrounding said vertical rod, said rod and sleeve having diametrically alining

15 apertures and a conductive wire support extending through the apertures and bent to form hooks upon either side of said rod and sleeve, to maintain themselves in immovable position and to maintain said sleeve relatively immovable upon said conducting rod.

In testimony whereof I affix my signature in presence of two witnesses.

MORTIMER L. PACKER.
